(57) CLAIM

The ornamental design of a lid for condiment dispenser, as shown and described.

DESCRIPTION

FIG. 1 is a perspective view of a lid for a condiment dispenser showing the new design in a partially open position with respect to a container;

FIG. 2 is a plan view of the lid for the condiment dispenser of FIG. 1 in a partially open position with respect to a container;

FIG. 3 is a side elevation view of the lid for the condiment dispenser of FIG. 1 in a partially open position with respect to a container; and,

FIG. 4 is a front elevation view of the lid for the condiment dispenser of FIG. 1.

The broken lines shown in the Figures are for illustrative purposes only and form no part of the claimed design.

The color in the Figures is not a feature of the design.
